UNITED STATES PATENT OFFICE.

WILLES W. ALLEN, OF BAKERSFIELD, CALIFORNIA.

TOBACCO PIPE.

Application filed March 28, 1921. Serial No. 456,397.

To all whom it may concern:

Be it known that I, WILLES W. ALLEN, a citizen of the United States, residing at Bakersfield, in the county of Kern and State 5 of California, have invented certain new and useful Improvements in a Tobacco Pipe, of which the following is a specification.

This invention relates to new and useful improvements in tobacco pipes, and has for 10 one of its objects to provide a device of this character which may be readily cleansed and kept from becoming foul by the collection of sediment in the stem or other parts and likewise providing for the ready cleansing 15 of the parts or the renewal of impaired or broken parts.

With these and other objects in view the invention consists of such novel features of construction as herein described and shown 20 and then specifically pointed out in the claims, and in the drawings illustrative of the preferred embodiment of the invention:—

Figure 1 is a longitudinal sectional elevation of the improved device.

Fig. 2 is a side elevation of the stem portion of the device detached.

Fig. 3 is a side elevation of tapered lining members of the improved pipe.

Fig. 4 is a view similar to Fig. 1, illustrating the manner of applying the improvement to a pipe having a curved tip or mouth piece.

The improved pipe comprises the usual 25 bowl 10 and stem 11, the latter having a longitudinal relatively large bore 16, communicating with the interior of the bowl centrally of its inner end.

Disposed within the bore of the stem is a 40 tapered lining 12 with the larger outer end flush with the outer end of the stem 11, as shown in Fig. 1.

The stem portion of the improved pipe, represented as a whole at 13 is formed with 45 a reduced terminal 14 provided with an annular shoulder 15. The reduced portion of the stem 13 is externally threaded, while the tapered lining 12 is internally threaded at its larger outer end so that the stem may be 50 readily attached to and detached from the tapered lining with the shoulder 15 bearing against the terminals of the stem and lining, as shown in Fig. 1. By this means the stem and mouth piece are joined without any ob-

struction or projection at their juncture as 55 shown in Fig. 1.

The bore of the lining 12 being larger at the outer end is gradually enlarged toward the mouth piece end, and the latter will be kept free from clogging as the draft in the pipe, 60 when in use, will be toward the larger end of the lining and thus carry sediment, if there be any, outwardly without danger of its engaging the sides of the lining and being 65 retarded thereby and choking the flow 70 through stem and the mouth piece. The lining member 12 will preferably be of a metal which will not corrode by the action of the tobacco or the moisture therefrom. The parts are easily detachable for cleansing 75 or repair or the renewal of impaired or broken parts.

The bore of the stem 11 is uniform throughout except at the inner end where it is reduced to receive the reduced inner end 75 of the lining 12, thus forming a relatively large space surrounding the lining for the greater part of its length. A dead air space is thus formed between the lining and the 80 body of the stem which serves as a non-conductor of heat.

The aperture in the bowl 10 with which the inner smaller end of the lining 12 communicates is located centrally of the tobacco receptacle, so that the suction is applied at 85 the center of the mass of tobacco in the bowl and thus insures a uniform and even burning.

The preferred embodiment of the invention is disclosed in the drawings and set 90 forth in the specification, but it will be understood that any modifications within the scope of the claims may be made in the construction without departing from the principle of the invention or sacrificing any 95 of its advantages.

Having thus described the invention what is claimed as new is:—

1. In a tobacco pipe, a bowl having a tubular stem internally tapered at the outer 100 end and with a passage at the inner end communicating with the bowl and internally tapered, a mouth piece reduced at the inner end with the reduced portion externally threaded, and a conductor member disposed within the tubular stem, the outer end 105 of the conductor being internally threaded to receive the externally threaded reduced

portion of the mouth piece and tapered externally at the outer end corresponding to and engaging the internal taper of the stem and externally tapered at the inner end corresponding to and closely engaging the tapered passage between the bowl and stem.

2. A tobacco pipe, comprising a bowl and stem with an internally tapered seat at the outer end and an internally tapered passage between the bowl and stem, a mouth piece reduced at the inner end, a conductor engaging over the reduced portion of the mouth piece and externally tapered to engage the tapered outer seat of the stem and rigidly supported between the stem and

mouth piece, the inner end of the conductor being externally tapered to engage the tapered passage.

3. A tobacco pipe, comprising a bowl and stem with an internally tapered seat at the outer end, a mouth piece reduced at the inner end, a conductor engaging over the reduced portion of the mouth piece and externally tapered to engage the tapered outer seat of the stem and rigidly supported between the stem and mouth piece. 20 25

In testimony whereof, I affix my signature hereto.

WILLES W. ALLEN.
